CLAIM

The ornamental design for a phone case, as shown and described.

DESCRIPTION

FIG. 1 is a front, right and top perspective view of the first embodiment of the phone case, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a front, left and top perspective view of the phone case of FIG. 1 in a usage state.

FIG. 10 is a front, right and top perspective view of a second embodiment of the phone case.

FIG. 11 is a rear, left and bottom perspective view thereof.

FIG. 12 is a front elevation view thereof.

FIG. 13 is a rear elevation view thereof.

FIG. 14 is a left side elevation view thereof.

FIG. 15 is a right side elevation view thereof.

FIG. 16 is a top plan elevation view thereof.

FIG. 17 is a bottom plan elevation view thereof; and,

FIG. 18 is a front, left and top perspective view thereof.

The broken lines depict portions of the phone case that form no part of the claimed design.
